DESIGN FOR AN INITIAL INDICATING BROOCH

Bernard Darvie, New York, N. Y.

Application August 5, 1939, Serial No. 86,476

Term of patent 7 years

To all whom it may concern:

Be it known that I, Bernard Darvie, a citizen of the United States, resident of the Bronx, in the county of the Bronx, city and State of New York, have invented a new, original, and ornamental Design for an Initial Indicating Brooch, of which the following is a specification, reference being had to the accompanying drawing, forming part thereof.

I claim:

The ornamental design for an initial indicating brooch, substantially as shown.

BERNARD DARVIE.
